UNITED STATES PATENT OFFICE.

OSCAR J. STREETZ, OF RIVER GROVE, ILLINOIS.

BASE-BALL-GAME APPARATUS.

1,135,338.

Specification of Letters Patent. Patented Apr. 13, 1915.

Application filed September 23, 1914. Serial No. 863,060.

To all whom it may concern:

Be it known that I, OSCAR J. STREETZ, a citizen of the United States, residing at River Grove, in the county of Cook and State of Illinois, have invented certain new and useful Improvements in Base-Ball-Game Apparatus, of which the following is a specification.

This invention relates to a base ball game apparatus, having reference more particularly to that type of such apparatus which employs a shallow box representing a base ball field, a mechanical device for impelling the ball from the batter's position into the field, and depressions or pockets in the field into which the ball comes to rest, each of such depressions representing a certain play that may occur in the regular game of base ball.

20 The object of my invention is to provide an improved device for impelling the ball from the batter's position at the home plate, and to this end the invention consists in an improved mechanical batter having the novel features of construction and mode of manipulation substantially as hereinafter described and pointed out in the claims.

In order that my invention and its mode of use may be clearly understood I have, in the accompanying drawings, illustrated the same in connection with a complete base ball game apparatus in which it is well adapted to perform its function, and referring thereto—

25 Figure 1 is a plan view of the apparatus with the exception of the chart or key; Fig. 2 is a cross section on the line 2—2 of Fig. 1; Figs. 3 and 4 are perspective elevations of differently colored disks used to represent the players of two opposing ball teams; Fig. 5 is a plan view of the chart or key; Fig. 6 is a perspective elevation of the mechanical batter; Fig. 7 is a vertical axial section of the mechanical batter, showing the ball set therein in position to be played.

Referring to the drawings, Figs. 1 and 2 show the main essential parts of the game apparatus, the same comprising a rectangular base-plate, conveniently formed in two superposed parts consisting of a lower solid or imperforate plate A and an upper perforated plate B resting thereon. On the upper surface of the plate B is printed or otherwise pictured a representation of a base-ball field, and from four edges of the plate A rise low bounding side and end walls

C and D, respectively; the parts thus far described having the general form and character of a shallow rectangular box body which may conveniently be made of heavy 80 cardboard, strawboard or the like.

The representation of the base-ball field on the upper surface of the bottom wall of the box body contains circles E, or other suitable markings to designate the bases and the fielders' positions, the home-plate being indicated by a diamond shaped marking F. At close intervals throughout the 85 outfit the upper plate B is formed with a plurality of circular apertures which, in conjunction with the lower plate A form shallow pits or pockets G, with each of which is associated an identifying symbol, preferably a numeral, as clearly shown in Fig. 1.

75 H and I designate, respectively, differently colored disks, as red and blue, of each of which a sufficient number are used to represent the players of two opposing teams. The excised disks that result from the perforating of the plate B may conveniently and economically be used for this purpose when properly colored or otherwise differentiated.

K designates the ball which may conveniently be simply a small wooden ball; and L designates as an entirety the mechanical batter forming the subject matter of this invention, the same comprising a hollow wooden block formed with a ball-receiving 80 hole M in its upper end, and a ball-discharging hole N in its side. Secured at its upper end in the block L, and projecting obliquely across the vertical bore of the block behind the delivery opening end is a 85 wire spring O, through the agency of which the ball is projected from the block in the manner hereinafter more particularly described.

Fig. 5 shows in plan view a chart or key 100 that is preferably, although not necessarily, employed in the playing of the game; this chart comprising one or more columns Q of the identifying numerals of the pockets G arranged in numerical order or sequence, 105 and directly opposite said numerals, a corresponding column or columns R of printed words defining the plays identified by the respective numerals opposite the same. These play-identifying indicia may be presented on any card or sheet accompanying the apparatus; but, where the latter is em-

bodied in the general box-like form herein shown, this chart is conveniently printed on the inner side of the box cover S, this later having side and end walls T and U, respectively, designed to fit over the side and end walls C and D of the body of the box when the apparatus is not in use.

The game may be played by two persons, each representing one of the opposing sides 10 or teams. If the side represented by the blue disks F is at the bat and the side represented by the red disks H is in the field, the various players' positions in the field are covered by red disks H, as shown in Fig. 1, 15 and the person who is playing the side represented by the blue disks places the mechanical batter L directly over the home plate F with the lateral opening N toward the field. He then places the ball K in the 20 top opening M of the batter and presses the same down with his finger. In so doing the spring O is tensioned rearwardly, and as soon as the ball comes into register with the side opening N it is projected through 25 the latter by the spring into and over the field, usually striking and rebounding from one or more of the bounding walls C and D, and coming to rest in one of the pockets G. As soon as the ball has thus come to rest 30 the play established by the shooting of the ball is determined by the identifying numeral of the pocket which the ball has reached, by reference to the chart if necessary. The ball is successively manipulated 35 in the same way, and a record is kept by the player of the successive plays thus made, until the side at the bat is retired under the regular rules of the game. When a one-base, two-base or three-base hit is secured, 40 a disk or chip representing the side at the bat is placed upon the first, second or third base, so that the apparatus to an extent affords a representation of the actual running of the bases by the players at the bat. 45 In Fig. 1 the field is represented with a runner on second base and a runner on third base. When one side is retired, it takes the field and the other side comes to bat, and the game proceeds in the manner already 50 described for the regulation nine innings or for such length as may be agreed upon between the persons playing the game. It is, of course, possible for the game to be played by a single person successively manipulating 55 the disks or chips representing the opposing sides or teams.

The mechanical batter L is of such a

character as to afford a considerable element of both skill and chance in placing the ball in the field. In the first place, it may 60 be set so that the opening N will point substantially to the center field or to the right or left field, so that a considerable variety in the general direction of projection of the ball is obtainable. The ball may also 65 be made to carom or rebound from one or more of the bounding walls, which adds a further feature of chance and skill. Still again, when the ball is depressed in the shooting block L by the finger of the operator, by giving the ball a slight turn or roll to one side or the other, the spring O can be made to impart a greater or less degree of "English" to the ball, somewhat as in the game of billiards, thereby introducing a 70 further factor of skill.

I claim:

1. A mechanical batter for a base-ball game apparatus, consisting of a hollow block having a hole to receive the ball, a hole in its side to discharge the ball, and a spring adapted to project the ball through the latter hole. 80
2. A mechanical batter for a base-ball game apparatus, consisting of a hollow block having a hole in its upper end to receive the ball, a hole in its side to discharge the ball, and a spring adapted to project the ball through the latter hole. 85
3. A mechanical batter for a base-ball game apparatus, consisting of a hollow block having a hole in its upper end to receive the ball, a hole in its side to discharge the ball, and an obliquely disposed spring adapted to be tensioned by the insertion of 90 the ball into the block and by its reaction to shoot the ball through the side hole when the ball comes into register with the latter. 95
4. A mechanical batter for a base-ball game apparatus, consisting of a hollow block having a hole in its upper end to receive the ball, a hole in its side to discharge the ball, and an obliquely disposed wire spring secured to the block at its upper end and free at its lower end adapted to be 100 tensioned by the insertion of the ball into the block and by its reaction to shoot the ball through the side hole when the ball comes into register with the latter. 105

OSCAR J. STREETZ.
